UNITED STATES PATENT OFFICE

HENRI P. L. LAUSSUCC, OF READING, PENNSYLVANIA, ASSIGNOR TO BIRDSBORO STEEL FOUNDRY & MACHINE COMPANY, OF BIRDSBORO, PENNSYLVANIA, A CORPORATION OF PENNSYLVANIA

SHEET PRESS AND METHOD

Application filed May 26, 1931. Serial No. 540,155.

My invention relates to the manufacture of pressed boards from finely divided fiber. This application is to some extent a continuation of my copending application, Serial No. 527,688, for sheet press and method, filed April 4, 1931.

One purpose of my invention is to provide desirable cycles of operation and mechanism adapted to perform the methods involved.

10 A further purpose is to equip a press, including a mold and a movable deckle, with novel means for controlling the drainage liquid from the mold.

15 A further purpose is to provide a water lock for retaining the drainage liquid in the mold during the filling of the mold with fiber or mush, and also during the operation of expelling the excess fiber or mush and the air from the mold.

20 A further purpose is to construct a water lock comprising a slide valve associated with the die which forms the bottom of the mold so that the slide will open and close the drainage grooves formed in said die.

25 A further purpose is to provide operating mechanism for opening and closing a slide valve and for normally holding the valve in the closed position.

30 A further purpose is to interconnect a water lock and the gates which admit the fiber or mush to the mold, so that the water lock is closed when the gates are in the open position.

35 A further purpose is to arrange troughs upon the lower die having outlet pipes connected with a sump, the troughs being positioned at the sides of the lower die for receiving the liquid from the ends of the drainage grooves formed in the lower die when the water lock is open.

40 A further purpose is to provide the lower die with a perforated plate for supporting a wire screen and to employ novel means for sealing the joints between the movable deckle and said perforated plate.

45 Further purposes will appear in the specification and in the claims.

My invention relates both to the methods or processes involved and to structure by 50 which the methods may be carried out.

I have elected to show one main form only of my invention, selecting a main form that is practical and efficient in operation and which well illustrates the principles involved.

Figure 1 is a side elevation of a press embodying my invention, shown partly in section, as on the line 1—1, Figure 2.

Figure 2 is a right end elevation of Figure 1, partly in section, as on the line 2—2 of Figure 1.

Figure 3 is an enlarged partial transverse vertical sectional view, as on the line 2—2 of Figure 1.

Figure 4 is a view similar to Figure 3, showing the parts in a different position.

Like numerals refer to like parts in all figures.

Describing in illustration and not in limitation and referring to the drawing:

55 Wet machines or presses for forming boards and sheets from paper pulp, leather fiber and other commercial fiber suspensions are well known, and therefore much of the illustration, although showing structure, is to be regarded as conventional. The primary purpose of all such machines is to press liquid, usually water, from the raw material suspension to form the raw material into a sheet.

60 For convenience in designation, I refer to the raw material, whatever its exact nature, as "finely divided fiber suspended in a liquid" or as "fiber", or "mush", and to the finished product, whatever its dimensions, as a "board" or "sheet".

65 Fiber suspensions are difficult to press chiefly because of the extreme readiness with which the fiber precipitates from the liquid. This tendency to precipitate makes it highly important to maintain the fiber flowing continuously in one direction, with as few interruptions as possible, to project the fiber laterally rather than vertically, avoiding sudden dropping into final position, to prevent

70 all escape of liquid suspension medium until precipitation is desired and to charge the mold rapidly and accurately without allowing air to be trapped in the mold.

75 In the ordinary wet machine the upper die

is smooth and the lower die is foraminated for removal of suspension medium.

While it is customary to construct wet machines with upper movable and lower stationary dies, and this form has therefore been illustrated in the figures, lower movable dies are sometimes used. It will be evident, of course, that my invention is equally applicable, whether the upper die alone, or the lower die alone, or both dies are movable.

While the upper and lower dies are of course press platens, the term platen is also applied to parts of the press located above or below the movable die, which are used to support the rams.

The principal parts of the illustrated wet board press or wet machine include a frame 10 consisting of top and bottom fixed platens 11 and 12 respectively, tension columns 13, an intermediate platen 14 and a surrounding deckle 15. The intermediate platen 14 is or carries the upper die and the bottom platen 12 is or carries the lower die.

The fixed platens 11 and 12 are rigidly secured together by the columns 13 and form the press frame 10. The movable or upper die 14 platen is positioned intermediate the fixed platens 11 and 12 and is slidably mounted upon the columns 13, which serve as guides. The upper die 14 is movable toward the bottom platen or the die 12 by main hydraulic rams 16 operatively mounted in cylinders 17, rigidly secured to the top platen 11. Said cylinders 17 have pipe connections 18 through which a pressure medium passes for forcing the rams 16 downwardly toward the lower fixed platen 12 which forms the lower die of the press.

The upper die 14 is moved upwardly by hangers 19 connected to the upper die 14 and suspended from cross-heads 20, which latter are lifted by retracting rams 21 operating in hydraulic cylinders 22, having suitable pipe connections 23. The cylinders 22 are rigidly mounted upon pedestals or bases 24 secured upon lugs 25 formed in the top overhanging portions of the top platen 11.

There are two of the retracting cylinders 22 located at opposite ends of the top platen 11. The retracting cylinders 22 are positioned upon the longitudinal center line of the top platen 11 and centrally of the cross heads 20. The cylinders 22 are arranged for lifting the cross heads, which in turn lift the movable platen or upper die 14.

The movable die may of course be equipped with equalizing mechanism to retain it horizontal at all times.

The movable platen 14 which forms the upper die is surrounded by a deckle 15 comprising longitudinal sides 26 and 27 located adjacent to the sides of the platen 14. The deckle 15 also includes transverse flow boxes 28 and 29 located adjacent to the ends of the platen 14. The flow boxes 28 and 29 are

rigidly connected with the ends of the deckle sides 26 and 27.

The deckle sides 26 and 27 are provided with lugs 30 which are slidably mounted upon the tension columns 13, thus making the deckle 15 movable relatively to the movable platen or upper die 14 and also to the lower die 12.

The deckle sides 26 and 27 carry vertical side liners 31 detachably secured to the deckle sides. The side liners 31 abut against the ends of vertical end liners 32 extending parallel with the flow boxes 28 and 29. The end liners 32 together with the side liners 31 form a parallelogram defining the sides and ends of the mold. The movable platen or upper die 14 is provided with vertical edge plates 33 which register properly with the deckle side liners 31 and end liners 32, sustaining the lateral wear on the die or movable platen 14 and insuring a working fit between the die 14 and the deckle 15, which is movable relatively to the die 14.

The flow boxes 28 and 29 receive the fiber, mush, or other material to be formed into sheets in the press. The mush may be supplied to the flow boxes 28 and 29 through suitable pipes, not shown in the drawing.

The flow boxes 28 and 29 have discharge openings 34, through which the mush flows upon the upper surface of the lower die 12, filling, or partly filling, the mold or space formed between the opposite deckle sides 26 and 27, when the deckle is in the lower position shown.

Stirrers 35 are located within the flow boxes 28 and 29 adjacent to the discharge openings 34, to keep the fiber from precipitating from its suspension medium in the flow boxes. The stirrers are rotated by any suitable means, not shown in the drawing.

Gates 36 are located in the deckle 15 for opening and closing the discharge openings of the flow boxes. The gates move vertically in suitable guides, not shown.

I use the work deckle in its broad sense to mean the lateral wall of the mold, including all inlet gates, vent gates, liners and confining walls whatsoever. I do not regard the distinction between the singular and the plural of the word deckle, nor between the side deckle and the end deckle, as critical.

The deckle 15, together with the flow boxes forming part of the deckle, is supported and vertically positioned by hangers 37, having their lower ends rigidly connected at 38 to the transverse deckle frame members 39 forming the inner walls of the flow boxes 28 and 29. The deckle frame members 39 are rigidly connected with the end plates 40 of the flow boxes, and the plates 40, in turn, are rigidly attached to the deckle sides 26 and 27. The upper ends of the hangers 37 are rigidly secured to cross heads 41, having their outer ends mounted upon deckle elevating rams 42,

which reciprocate in hydraulic cylinders 43 rigidly secured at their lower ends upon extension brackets 44 formed upon the upper platen 11. The cylinders 43 are provided with suitable pipe connections 45 for the admission or exhaust of a pressure medium to lift or permit lowering of the deckle elevating rams 42.

The gates 36 extend across the full length 10 of the flow boxes 28 and 29. Upon each gate 36, preferably located adjacent to its center, is secured a superstructure 46, having its upper end attached at 47 to a gate closing ram 48. There is a ram 48 for each gate 36. The rams 48 are operatively mounted in cylinders 15 49 having fluid connections 50, through which a pressure medium is preferably constantly supplied to the cylinders 49.

By this arrangement the gates 36 are normally pressed downwardly into the closed position, as shown in the drawing. The cylinders 49, containing the gate closing rams 48, are rigidly mounted upon brackets 51, by tie rods 52. The brackets 51 are mounted 25 upon the retracting cylinders 22, as shown in Figure 1.

The gates 36 are adapted to be lifted against the steady downward urging of the constant pressure rams 48, without lifting the deckle 15, by means of rocker arms 53 which make connection with slotted links 54 by means of pins 55. The lower ends of the slotted links 54 are pivotally connected at 56 with the gate 36.

The rocker arms 53 are rigidly fastened to a rocker shaft 57, journaled in suitable bearings 58 on the top platen 11, and connected through a crank 59 and a connecting rod 60 with a horizontal gate-opening ram 61, in a cylinder 62 and having a fluid connection at 63.

A smaller ram 64, having a cylinder 65 and a fluid connection 66, is integral with and opposed to the gate-opening ram 61, and the smaller ram 64, being preferably under constant pressure, heavily retracts the gate-opening ram 61 and thereby the rocker shaft 57 to the position corresponding with gate closure.

The slotted links 54 engaging the pins 55 permit upward movement of the deckle 15, including the gates 36, as a single unit without changing the positions of the rocker arms 53, and, if the deckle is all the way down, permit opening and closing of the gates without movement of the deckle. The gates 36 lift against the downward pressure of the constant pressure rams 48 by the action of the horizontal gate-opening ram 61 through the rocker shaft 57 and links 54, and close by action of the constant pressure rams 48, upon releasing the horizontal gate-opening ram 61. The constant pressure ram 64 returns the gate-opening ram 61 to its original position and at the same time returns the

rocker arms 53 to starting position, acting through a connecting rod 60, a crank 59 and a shaft 57.

When the deckle is raised, the gates are normally always closed under the heavy 70 downward retraction from the constant pressure rams 48.

Desirable features of my invention are included in the structure of the flow boxes, which cooperate with the remainder of the 75 mold to permit simultaneous adjustments of the rest positions of the die and of the quantity of fiber delivered from the boxes into the mold during each cycle of the wet machine.

As previously noted, it is important to prevent escape of water or other mush suspension medium from the mold during filling, and where overfilling is performed, during squeezing out of the excess mush from the mold. This prevention of liquid escape is commonly called "water locking." On the other hand, it is important that free liquid escape be possible during pressing of the mush into a sheet.

The bottom die 12 carries a filter bed permitting easy downward expression of water from the mush.

As illustrated, the top 67 of the bottom die 12 is provided with a succession of transverse drainage grooves 68. The grooved surface is covered by a foraminated plate 69, which is in turn covered by a movable screen or wire 70 of perhaps 40 or 60 mesh, desirably shifted and washed after forming each sheet. 106 The wire extends over pulleys 71 and 72, of which 72 is driven by a motor 73.

Provision is made for preventing the downward escape of water from the mush during the period that the mush is filling the mold, 105 until the mush has reached its filling level and preferably until the upper die 14 has moved down and squeezed out any excess of mush which is to be removed from the mold, thus avoiding uneven precipitation of 110 fiber in the mold and lines of weakness in the formed sheet where fiber masses separately precipitated meet but fail to interlock because they have not settled exactly together.

A desirable feature of my invention is directed to the construction of the water lock on the bottom die 12 and to waterlocking the mold while the mush is entering the mold and until the upper die 14 has expelled the air and/or excess mush from the mold and is ready to start upon its final downward pressing stroke. The water lock must not remain open for a sufficient time before the beginning of the pressing stroke of the die to allow 120 drainage to lower the mush level and thus produce a void which the air will fill; nor should the die 14 start its final pressing stroke while the gates 36 are open appreciably.

The water lock illustrated in the drawing 125

comprises slide valves having slides 74 positioned vertically at opposite sides of the lower die 12. The slides 74 are movable vertically between the vertical side surfaces of the lower die 12 and troughs 75, rigidly mounted upon the opposite sides of the lower die 12.

Said troughs 75 are U-shaped in cross-section, having side walls 76 and 77 and a bottom wall 78. The inner side walls 77 are secured 10 in spaced relation with respect to the vertical side surfaces of the lower die 12, thus forming vertical guides for the valve slides 74.

The inner walls 77 of the troughs 75 terminate below the level of the drainage grooves 15 68, so that the suspension medium, ordinarily water, from the latter may run into the troughs 75, when the water lock or valve slides 74 are moved downwardly. The slides 74 will preferably be moved downward 20 until the upper edges of the slides 74 are below the bottom of the drainage grooves 68.

The troughs 75 have pipes 79 leading to any suitable drain or sump. The outer walls 76 of the troughs preferably extend to a sufficient height to form a tight joint with the outer edge portions 80 of the foraminated plate 69 which is supported upon the grooved top surface of the lower die.

The outer edge portions 80 of the plate 69 30 are not perforated beyond the mold as defined by the vertical liners 31 of the deckle sides 26 and 27.

The lower surface of the deckle 15 is provided with a pad or gasket 81, preferably of 35 rubber or leather, which rests upon the edges of the wire 70 and presses the edges of the wire upon the unperforated outer portions 80 of the plate 69 when the deckle is in its lower position, preventing the escape of mush and 40 liquid between the plate 69 and the deckle and directing the water or other suspension medium through the perforations in the plate 69 to the drainage grooves 68 formed in the die 12, from which it flows into the trough 75 45 when the valve slides 74 are open, as shown in Figure 3.

When the valve slides 74 are closed, as shown in Figure 4, the water is retained in the grooves 68 and also in the mush, since the 50 upper edges of the valve slides 74 form a tight joint with the under surfaces of the unperforated portions 80 of the foraminated plate 69.

The valve slides 74 are held in the closed 55 position, as shown in Figure 4, by lever arms 82 pivoted upon pins 83 secured in lugs 84, formed upon the lower die 12. The lever arms 82 carry weights 85 at their outer ends and are connected with links 86 at their other 60 ends. The links 86 connect with the valve slides 74.

The valve slides 74 are preferably always tightly closed if the gates 36 are open, so that the closed water lock will prevent the drainage 65 of liquid from the mush during the filling

of the mold. When the gates 36 are closed, as shown in Figure 1, the valve slides 74 are opened to permit the water to drain from the mush during the pressing of the latter by the movable die 14.

The slides 74 are automatically opened by closing of the gates 36 by means of flexible connections 87 attached at their lower extremities to the weighted ends of the lever arms 82.

The flexible connections 87 pass over guide pulleys 88 mounted upon the upper platen 11, and also around drums 89, secured upon the opposite ends of the rocker shaft 57. The flexible connections are coiled about the drums 89 in a direction such that the flexible connections wind upon the drums when the rocker shaft 57 is turned into the position to close the gates 36, thus lifting the weighted ends of the lever arms 82, and thereby moving the valve slides 74 into the open position. Through the opposite rotation of the shaft 57, the flexible connections will unwind due to the direction of winding on the drums 89, thus allowing the weights 85 to move the lever arms 82 into a position to close the slides 74 as shown in Figure 4. The open position of the valve slides 74 forming the water lock corresponds to the closed position of the gates 36.

When the deckle 15 is raised, the gates 36 always remain in the closed position for retaining the mush within the flow boxes 28 and 29.

The operation of my invention is as follows:—

The deckle 15 is raised to the position shown in Figure 1 and the previously formed sheet is removed from the mold by hand or upon any suitable transfer mechanism. Then the deckle 15 is lowered to the position shown in Figures 2, 3 and 4. The flow boxes 28 and 29 have been previously filled with mush for forming the next sheet.

During all of these steps the water lock is not functioning, and, in the form here shown, is open. It is desirable that the water lock be open when the sheet is lifted from the bottom die, so that access of air is possible between the die and the sheet.

The gates 36 are opened so that the mush flows from the flow boxes into the mold, covering the wire 70 and filling the area of the mold defined by the vertical walls of the deckle. Simultaneously with the opening of the gates the water lock closes.

If the upper die 14 is in such a position that the mold capacity corresponds with the quantity of mush to be used in making the sheet, the gates may then be closed, and the water lock simultaneously opened. Then the sheet may be formed by expressing the water or other suspension medium.

I prefer, however, to fill the mold at a time when the mold capacity exceeds the volume

of mush to be used in forming the sheet. In this mode of operation, with the gates 36 remaining open, the upper die is moved downwardly upon the mush in the mold while 5 the gates are open, thus allowing the air from above the mush and the excess mush to be returned to the flow boxes 28 and 29 through the open gates. During this portion of the operation the water locks are 10 closed by the weighted lever arms 82, thus preventing the drainage of liquid from the mush during the period that the mush is filling the mold and until the mush has reached its filling level, and preferably until 15 the upper die 14 has moved down and squeezed out any excess of mush which is to be removed from the mold, thus avoiding uneven precipitation of fiber in the mold and lines of weakness in the formed sheet where 20 fiber masses separately precipitated meet but fail to interlock because they have not settled exactly together.

When the gates 36 are closed, the water locks are automatically opened, so that the 25 upper die 14 may perform its pressing operation and force the water from the mush into the drainage grooves 68 formed in the lower die 12. From the grooves the water flows over the opened valve slides 74 and into 30 the troughs 75, from which it is carried away through the drainage pipes 79.

When the upper die 14 has completed the pressing operation, the deckle 15 may be lifted, with the gates 36 in the closed position. 35 The upper die 14 may be elevated into the position shown in Figure 1, so that the finished sheet may be removed from the press in a manner well known in the art.

When operating my wet machine by over- 40 filling the mold and then squeezing out the excess of fiber through the gates, I will move the upper die 14 relatively toward the lower die 12 until the excess of mush has been squeezed from the mold, and then slow down 45 or preferably stop the upper die movement until the gates have been closed before pressing the fiber into a sheet.

The range of movement of the gates and the water lock valve slides will preferably be 50 such that the water lock closes fully before the gates open.

It will be evident that my invention is particularly advantageous in large machines having lower dies provided with numerous drainage channels, since I individually close the drainage channels when my water lock is closed. On the other hand, when my water lock is open each drainage channel communicates directly with a header so that there is 55 no possibility of clogging in the water lock valve.

In my preferred form the valve extends the full length of the drainage channels so that the drainage cross section at the valve 60 is equal to or greater than the drainage cross

section in the channels when the valve is open.

By using the side wall of the lower die and the side of the drainage header as guides for my valve slide, I greatly simplify the mechanism. 70

The vertical form of slide valve is considered by me to be preferable, but it will of course be apparent that slide valves may be disposed in various manners, either vertically 75 or horizontally and that they may act against the plate 69, against the lower die 12, or against special seats provided in the mechanism.

While I have illustrated and specifically 80 described a form of my invention in which the water lock and the gate actuating mechanism are mechanically interconnected, it will be evident that the interconnection may be made hydraulic means are well known, and I 85 consider that the principal features of my invention are sufficiently illustrated by describing the mechanical form.

I believe that I am the first to interconnect 90 a water lock with the flow box gates of a wet machine so that the water lock is closed when the gates are open and open when the gates are closed.

I also believe that I am the first to close 95 the individual horizontal drainage channels of a wet machine die between the drainage channels and a header.

In view of my invention and disclosure variations and modifications to meet individual 100 whim or particular need will doubtless become evident to others skilled in the art, to obtain part or all of the benefits of my invention without copying the structure shown, and I, therefore, claim all such insofar as they fall within the reasonable spirit and scope of 105 my invention.

Having thus described my invention, what I claim as new and desire to secure by Letters Patent is:

1. The method of preparing a sheet from 110 finely divided fiber suspended in a liquid within a mold having a relatively movable top and bottom, which consists in filling the entire mold with fiber to a depth greater than that required to produce a sheet, in expelling the excess of fiber from the mold, in closing the mold against drainage, preventing drainage of liquid from the mold while expelling the excess of fiber and suspension from the mold, and in pressing the remaining fiber into 115 a sheet.

2. The method of preparing a sheet from 120 finely divided fiber suspended in a liquid within a mold having a relatively movable top and bottom, which consists in filling the entire mold with fiber to a depth greater than that required to produce a sheet, in expelling the excess of fiber from the mold by moving the mold top and bottom relatively closer together while restraining drainage from the 125 sheet. 130

mold bottom, in decreasing the rate of relative movement of the mold top and bottom while preventing further escape of fiber from the mold and permitting drainage and in pressing the remaining fiber into a sheet.

3. In a wet machine of the type having upper and lower dies and a deckle, a lower die having water carrying passages communicating with a common discharge outlet and a water lock shutting off the individual passages.

4. In a wet machine, upper and lower dies, a deckle, the lower die having water carrying passages communicating with a common discharge outlet, a water lock shutting off the individual passages, and a gate in the deckle interconnected with the water lock to release the water lock when the gate closes.

5. In a wet machine, upper and lower dies, a deckle, the lower die having water carrying passages communicating with a common discharge outlet, a water lock shutting off the individual passages, a gate in the deckle, an upper die adapted initially to engage and come to rest against a charge in the mold while the gate is open and operating connections releasing the water lock when the gate closes.

6. In a wet machine, relatively movable upper and lower dies, a deckle, a gate in the deckle, a water lock for the lower die and cooperative connection between the water lock and the gate to maintain the water lock closed while the gate is open and to maintain the water lock open while the gate is closed.

7. In the operation of a wet machine having a mold, a gate and a water lock, the art which consists in coordinating the closing of the water lock and the opening of the gate.

8. In the operation of a wet machine having a mold, a gate and a water lock, the art which consists in coordinating the closing of the water lock and the opening of the gate and in closing the water lock before the gate opens.

9. In a wet machine, upper and lower relatively movable dies, a deckle movable relatively to said dies, said deckle forming the vertical walls of a mold, said lower die forming the bottom of the mold, a water lock located at the edge of the lower die adjacent the deckle arranged for retaining liquid within the mold and means for opening and closing the water lock.

10. In a wet machine, upper and lower relatively movable dies, a deckle movable relatively to said dies, said deckle forming the vertical walls of a mold, said lower die forming the bottom of the mold, and a valve slide movably mounted upon the lower die arranged for retaining liquid within the mold.

11. In a wet machine, upper and lower relatively movable dies, a deckle movable relatively to said dies, said deckle forming

the vertical walls of a mold, said lower die forming the bottom of the mold, a valve slidably mounted upon the lower die, said lower die having a drainage groove formed therein, and means for moving the valve for opening and closing said drainage groove.

12. In a wet machine, upper and lower relatively movable dies, a deckle movable relatively to said dies, said deckle forming the vertical walls of a mold, said lower die forming the bottom of the mold, a drainage trough mounted upon the lower die, said lower die having drainage grooves formed therein communicating with said trough, a valve slide located between said trough and the lower die, and means for moving the slide into a position to close communication between the drainage groove and the trough.

13. In a wet machine, upper and lower relatively movable dies, a deckle movable relatively to said dies, said deckle forming the vertical walls of a mold, said lower die forming the bottom of the mold, a sealing member located between the deckle and the lower die, said lower die having a drainage groove formed therein located below said sealing member, and means for opening and closing said drainage groove.

14. In a wet machine, upper and lower relatively movable dies, a deckle movable relatively to said dies, said deckle forming the vertical walls of a mold, said lower die forming the bottom of the mold, a perforated plate upon the top face of the lower die, said lower die having drainage grooves formed therein below said plate, a sealing member located between the deckle and the outer edge portions of said plate, and a valve arranged for opening and closing said drainage grooves.

15. In a wet machine, upper and lower relatively movable dies, a deckle movable relatively to said dies, said deckle forming the vertical walls of a mold, said lower die forming the bottom of the mold, a perforated plate upon the top surface of the lower die, a wire screen upon said plate, said plate and said screen having their edges extending under the deckle, a pad upon the lower face of the deckle arranged to form a sealing member between the deckle and said plate, said lower die having drainage grooves formed therein below said plate, and a valve arranged for opening and closing said drainage grooves.

16. In a wet machine, upper and lower relatively movable dies, a deckle movable relatively to said dies, said deckle forming the vertical walls of a mold, said lower die forming the bottom of the mold, a plate upon the top surface of the lower die and projecting beyond the edges of the lower die, said plate having perforations therein located above said lower die, said lower die having drainage grooves formed therein below said plate, and a valve slidably mounted upon the side

of the lower die arranged for closing said grooves when the edge of the valve abuts against the under surface of said plate.

17. In a wet machine, upper and lower relatively movable dies, a deckle movable relatively to said dies, said deckle forming the vertical walls of a mold, said lower die forming the bottom of the mold, said lower die having drainage grooves formed in the top surface thereof, a valve slidably mounted upon the lower die and movable transversely relatively to said grooves for closing the latter, a trough, mounted upon the lower die adjacent to said valve, with which said drainage grooves communicate when the valve is positioned to open said grooves, a plate upon the top surface of the lower die having its outer edge portions projecting over the valve and trough, forming a cover for the latter, and said plate having perforations communicating between the mold and said grooves.

18. In a wet machine, upper and lower relatively movable dies, a deckle movable relatively to said dies, said deckle forming the vertical walls of a mold, said lower die forming the bottom of the mold, vertical guides upon the side of the lower die, and a valve slide movably mounted in said guides, whereby the upper edge of the valve slide may be positioned to retain liquid within the mold.

19. In a wet machine, upper and lower relatively movable dies, a deckle movable relatively to said dies, said deckle forming the vertical walls of a mold, said lower die forming the bottom of the mold, vertical guides upon the side of the lower die, a valve slide movably mounted in said guides, and a counter balance operatively associated with the valve slide arranged for normally positioning the top edge of the valve slide to retain liquid within the mold.

20. In a wet machine, upper and lower relatively movable dies, a deckle movable relatively to said dies, said deckle forming the vertical walls of a mold, said lower die forming the bottom of the mold, vertical guides upon the side of the lower die, a valve slide movably mounted in said guides, an arm pivotally mounted upon the lower die having one end operatively associated with the valve slide, a weight upon the opposite end of said arm arranged for normally positioning the valve slide relatively to the top surface of the lower die for retaining drainage liquid in the mold.

21. In a wet machine, upper and lower relatively movable dies, a deckle movable relatively to said dies, said deckle forming the vertical walls of a mold, a gate upon the deckle for controlling a passageway to and from the mold, a water lock upon the lower die, and means operatively associated with the gate and the water lock to maintain the water lock open when the gate is closed.

22. In a wet machine, upper and lower relatively movable dies, a deckle movable relatively to said dies, said deckle forming the vertical walls of a mold, a gate upon the deckle for controlling a passageway to and from the mold, a water lock positioned on the lower die adjacent the deckle, means operatively associated with the water lock to maintain the same normally in a position to hold liquid within the mold, and means operatively associated with the gate and the water lock to maintain the water lock open when the gate is closed.

23. In a wet machine, upper and lower relatively movable dies, the lower die having drainage outlets, and a deckle for one of the dies, forming a mold, a flow box, a gate between the flow box and the mold, means for raising and lowering the gate, a source of material to be pressed, means for charging the mold with the material in excess of the intended ultimate depth of charge, movable dies means for squeezing back into the flow box the excess of charge, means for closing the gate while the excess charge is so held back, a water lock arranged for closing the drainage outlet through the lower die, and cooperating means between the gate and the water lock for opening the latter when the gate is closed.

24. In a wet machine, an upper fixed platen, a lower fixed die, columns rigidly connected with said upper platen and said die, a die movably mounted upon the columns, a deckle movably mounted upon the columns forming a mold when positioned upon the lower die, a flow box upon the deckle, a gate between the flow box and the mold for controlling the flow of fiber between the flow box and the mold, a shaft rotatably mounted upon the fixed platen, means for rotating said shaft, mechanism operatively associated with the shaft and the gate for opening the gate by the rotation of the shaft, a water lock mounted upon the lower die, means for normally closing the water lock arranged to retain water within the mold, a drum upon said shaft, and a flexible connection upon said drum having its opposite end connected with the water lock arranged for opening the water lock when the shaft is turned to gate closing position.

25. In the operation of a wet machine having a mold, a gate and a water lock, the art which consists in coordinating the closing of the water lock and the opening of the gate and in closing the water lock concurrently with the opening movement of the gate.

26. In a wet machine, upper and lower relatively movable dies, a deckle movable relatively to said dies, said deckle forming the vertical walls of a mold, said lower die forming the bottom of the mold, a plurality of water locks located at respective edges of the lower die adjacent the deckle arranged

for retaining liquid within the mold and means for concurrently opening and closing all of the water locks.

27. In a wet machine, upper and lower 5 relatively movable dies, a deckle movable relatively to said dies, said deckle forming the vertical walls of a mold, said lower die forming the bottom of the mold, a plurality 10 of valves slidably mounted upon different edges of the lower die, said lower die having drainage grooves formed therein and means for concurrently moving the valves for opening and closing the drainage grooves.
